UNITED STATES PATENT OFFICE.

WILLIAM E. HANSCOM, OF PORTLAND, OREGON, ASSIGNOR OF FORTY PER CENT TO
MIKE KLIGMAN, OF PORTLAND, OREGON.

SELECTIVE GUMMED-TAPE-DISPENSING MACHINE.

Application filed November 23, 1925. Serial No. 70,871.

My invention relates to machines for the dispensing of gummed tape, the tape dispensed to be used in the wrapping of packages and the like as a substitute for cord or string, and has for its object the carrying within the frame of one or more widths of tape, power means for dispensing the same and selective means for dispensing the width of tape required for the package or article to be wrapped.

A further object of my machine consists in providing means within the machine for moistening the gummed surface of the tape, as the same is being dispensed.

15 A further object of my device, consists in providing a manipulating hand member adapted to complete an electric circuit, by the same being depressed selective means is provided for selecting the desired width of 20 the tape to be dispensed, and when the circuit has been completely broken and the desired amount of tape having been dispensed, the return of the hand member to normal position, will automatically cut the tape dispensed through the action of the shearing blade carried on the lower end of the same.

25 A further object of my invention, consists in the arrangement of the parts in such a manner that the cutting of the tape is made upon the unmoistened portion of the tape.

30 With these and incidental objects in view, the invention consists in certain novel features of construction and combination of parts, the essential elements of which are set forth in the appended claims, and a preferred form of embodiment of which is herein-after shown with reference to the drawings which accompany and form a part of this specification.

35 In the drawings:—

Fig. 1 is a longitudinal cross section view of the machine, taken on line 1—1 of Fig. 2.

40 Fig. 2 is a plan view of the assembled machine partially in section and with a part of the case of the machine shown removed.

45 Fig. 3 is a partially inverted plan view, taken on line 3—3 of Fig. 1, looking in the direction indicated.

50 Fig. 4 is a plan view of the manipulating hand member, located above the stem to which it is attached and the contact point for manipulating the selective release of the tape to be used.

55 Fig. 5 is a cross section view, taken on

line 5—5 of Fig. 1, looking in the direction indicated.

Fig. 6 is a cross section view, taken on line 6—6 of Fig. 1, looking in the direction indicated.

Fig. 7 is a perspective view of the knife and stem for manipulating the selective feed and for cutting the ribbon when desired.

Fig. 8 is a cross section view of the knife end of the guideways for supporting the same.

Like reference characters refer to like parts throughout the several views.

1 is the base of the machine, having side wall frame members 2, disposed upon either side of the base and extending practically vertical from the base. A shaft 3, is maintained within the side wall members 2, in suitable bearings and is held in position by thumb nuts 4 and 5, disposed on either end of the same. Mounted upon this shaft are one or more rolls of gummed paper, here shown as two in number, as shown at 6 and 7, the same being positioned upon the shaft by a spacer 8, which is secured to the wall structure of the machine by a suitable fastening means as a screw 9. Different sized spacers may be used to accommodate different width of rolls. The gummed paper is conducted from the roll through channel guideways or tubes 10 and 10^A, and passes between the feed rolls 11 and 12 and 29 and 29^A. The lower feed rolls 11 and 29^A are mounted on a rocking support or yokes 11^A and 29^B respectively, which are rockably mounted about shaft 13, secured to the side wall members of the machine. A power unit 14, as an electric motor, is mounted upon a base support 15, within the frame structure and is energized through an electric circuit, through the electric cords 16 and 17, which are connected to an outside source of electric energy.

When it is desired to secure gummed tape from the machine, the operating handle or knob 18, is lowered by the hand of the operator. If it is desired to secure a wide tape, the operating handle which is freely mounted on the sliding stand 24, is turned until the contacting arm 19, is made to engage with the trip 20^A, which is normally held in raised position through the action of compression spring 21^A, supported upon the bracket 22, at which time the lower feed

roll 29^A, is disengaged from indirect contact with the underside of roll 29 disposed thereabove, and with the broad gummed tape. The further depression of the knob 18, causes the electric switch member 23, which is mounted to the vertical stem 24 to contact with the switch member 25, thus closing the electric circuit to the power unit 14, is then energized, turning the armature 10 of the motor and the worm 26, which is secured to the shaft thereof. The worm 26, engages the worm wheel 27, which is mounted on the shaft 27^A which is rotated thereby. The shaft 27^A also carries the feed rolls 29, 15 and 12 which are rotated thereby, the roll 29 feeding the wider gummed tape from the roll 7. The side wall members 30 and 30^A are positioned parallel to each other, and are spaced apart sufficiently to permit the stem 20 24, to freely slide therebetween. The side wall members are each provided with openings of size and shape equal to the size and shape of the interior of the tubes 10 and 10^A. The lower end of the stem 24 is broadened 25 out into a rectangular plate 24^A, and the holes 28 and 28^A are formed through this plate. The lower edge of each of the holes 28 and 28^A are formed at an angle to the horizontal as shown at 28^B and 28^C, to form 30 the cutting edges or knives of my device. The normal position of the stem 24, is such that the holes 28 and 28^A are positioned above the tubes 10 and 10^A. In operation the knob 18 is depressed, which depresses 35 the plate 24^A so that the holes 28 and 28^A will register with the tubes 10 and 10^A, and tape will pass through one or the other of the holes through the plate 24^A; and if the knob is released, the stem 24 and the plate 40 24^A will rise to normal position, brought about by means of a spring 38, hereinafter described, the electric circuit to the motor 14 will be opened and the motor and machine stopped, and the paper strip passing 45 through the machine will be cut by one or the other of the cutting edges or knives 28^B and 28^C as the case may be. The depression of the knob or handle 18, depresses the stem 24, also, and in doing so, the openings 28 50 and 28^A, are made to register with the openings 10 and 10^A through the side wall members 30 and 30^A which form a guideway for the stem and which is best shown in Fig. 8. This permits the gummed tape to pass 55 through the opening 28.

A liquid, as water, is contained within the basin 31, in which the wetting roll 32, rotates. The tape comes in contact with the wetted roller through the action of a holding 60 down roller 33, disposed above the roller 32. The roller 32 is freely mounted upon the shaft 37^A, and rotation is imparted to it by engagement with the roller 33 which is rotated by means hereafter explained. The shaft 37 mounting the roll 33, is revolvably

mounted to the outer ends of each of the arms 37^A and 37^B, the inner ends of said arms being loosely mounted to the shaft 27^A. An engaging train of revolvable gears 34, 35, and 36 are mounted respectively to the shaft 70 27^A, to the arm 37^A intermediate its ends, and to the shaft 37; and it will be seen that when the shaft 27^A is rotated, shaft 37 with its associated roll 33 will also be rotated. The roll 33 normally rests upon and rotates 75 the roll 32, and will rotate roll 32 when it, itself is rotated. The paper strip passes between the two rolls 33 and 32 when they are rotating, and as the strip passes between the rolls, the under or coated side of the paper 80 will receive moisture from the wetting roll 32.

Moistened tape of the selected width will be dispensed through this train of movements and over the wetted roll until the 85 desired length has been secured, at which time the operator's hand is removed from the knob 18, which permits the return of the stem 24, which breaks the circuit and stops the motor on the upward movement 90 of the stem, which is caused by the action of the compression spring disposed about the stem, as shown at 38. The spring 38 is compressed on the downward movement of the stem and which automatically returns the 95 stem to normal position when the knob 18 is released.

Should it be desired to dispense the narrow gummed tape, the contacting arm 19, is moved to engage with the trip 20^A as 100 best shown in Fig. 5, at which time the same train of operations are set in motion, with the exception that the hinged feed roll 11, disposed beneath the wide gummed tape to feed the same, is disengaged from roll 12, and the wide tape 7 is not drawn from the roll and upon the actuation of the machine the narrow tape 6 only is dispensed.

Should it be desirable to dispense both narrow and wide at the same operation, the 110 same may be accomplished by the permitting of the contacting point 19, to be depressed without contacting with either of the rolls at which time the same train of mechanisms will be set in operation, with the exception that both narrow and wide gummed tape will be dispensed to the required length, after which time the train of operations are stopped and the hand devices are permitted to return to normal position, 115 at which time both narrow and the wide gummed tape are sheared off on the return of the hand device.

The hand device may be rotated within certain limits, the movement of which is 125 governed by the stop pins or guides 40 and 41, disposed at either side of the same. To facilitate the engagement of the contacting arm 19, with either of the trips 20 and 20^A the same is made to contact with either of 130

the stop pins 40 or 41, and when depressed is positioned directly over the trip for disengaging one of the feed rolls. This is shown in the position of the contacting arm 19, engaging with the stop pin 40, in Fig. 4. The arm 19 being shown in dotted position.

5 While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the 10 claims which follow.

15 What I claim is:—

1. In a selective gummed tape dispensing machine, a frame, paper roll suspension means in said frame; guide tubes leading to 20 passageways through a vertical guideway; guide tubes leading from said passageways to a moistening roll; a shaft mounted transversely of said frame, a pair of rolls on said shaft, a pair of yokes rockably mounted below said shaft; a roll on each yoke engaging the first mentioned rolls, a vertical guideway provided with transverse passageways; a stem slidable in said guideway; a plate formed on the lower end of said stem 25 provided with passageways, shears formed in said last mentioned passageways; a spring upon said stem normally maintaining the last mentioned passageways elevated above the first mentioned passageways; a knob freely mounted to the upper end of said stem; vertical trips connected to the free end of each yoke; an arm on said knob to engage either of said trips when said stem is depressed; a pair of arms pivoted at their inner ends to said shaft; a roll revolvably mounted at the outer ends of said arms; a train of gears connecting said last mentioned roll to said shaft; an idler moistening roll mounted below the last mentioned roll and 40 operated thereby; an electric motor to operate said shaft; and mechanism associated with said stem to stop and start said motor.

2. In a selective gummed tape dispensing machine, a frame, paper roll suspension 50 means in said frame; a shaft mounted transversely of said frame, a pair of rolls on said shaft; a pair of yokes rockably mounted below said shaft; a roll on each yoke engaging the first mentioned rolls; a pair of spaced plates vertically mounted to form a guideway; passageways formed through said plates for the passage of tape therethrough; a stem vertically slidable between said plates; a plate formed on the lower end of said stem 55 provided with passageways to embrace the passageways in the first mentioned plates; said last passageways having their lower edges disposed to form diagonal shearing blades; a spring upon said stem normally

60 maintaining the last mentioned passageways elevated above the first mentioned passageways; a knob freely mounted to the upper end of said stem; trips, slidable vertically, connected to the free end of each yoke; springs maintaining said trips at the limit 70 of their upward movement; an arm on said knob to engage either of said trips when said stem is depressed; an idler moistening roll mounted in said frame; a rocking support mounted to the aforementioned shaft, a 75 roll mounted to said rocking support and connected to said shaft by a train of gears; said last mentioned roll normally resting upon and engaging the moistening roll; an electric motor to operate said shaft; and 80 mechanism associated with said stem to stop and start said motor when said stem is in raised and lowered position respectively.

3. In a selective gummed tape dispensing machine, a frame, paper roll suspension 85 means in said frame; a shaft mounted transversely of said frame, a pair of rolls on said shaft; a pair of yokes rockably mounted below said shaft; a roll on each yoke engaging the first mentioned rolls; a pair of 90 spaced plates vertically mounted to form a guideway; passageways formed through said plates for the passage of paper tape therethrough; a stem vertically slidable between said plates; a plate formed on the lower end of said stem 95 provided with passageways to embrace the passageways in the first mentioned plates; said last mentioned passageways having their lower edges disposed to form diagonal shearing blades; a spring 100 upon said stem normally maintaining the last mentioned passageways elevated above the first mentioned passageways; a knob freely mounted to the upper end of said stem; trips, slidable vertically, connected to the free end of each yoke; springs maintaining 105 said trips at the limit of their upward movement; an arm on said knob to engage either of said trips when said stem is depressed; an idler moistening roll mounted in said frame; a rocking support mounted to the aforementioned shaft, a roll mounted to said rocking support and connected with said shaft by a train of gears; said last mentioned roll freely resting upon and engaging the moistening roll; guide tubes leading 115 from a point adjacent said paper roll suspension means to the passageways in one of the plates forming the guideway; guide tubes leading from the passageways in the other of said plates, to a point adjacent the moistening roll; an electric motor to operate said shaft; and mechanism associated with said stem to stop and start said motor when said stem is in raised and lowered position respectively.

120 WILLIAM E. HANSCOM.
